Merle L. Barr
ATTORNEY

UNITED STATES PATENT OFFICE.

OLIVER S. JENNINGS, OF MANSFIELD, OHIO, ASSIGNOR TO WESTINGHOUSE ELECTRIC & MANUFACTURING COMPANY, A CORPORATION OF PENNSYLVANIA.

INCLOSED SWITCH.

Application filed April 22, 1927. Serial No. 185,694.

My invention relates to inclosed switch mechanisms and particularly to mine switches.

One object of my invention is to provide 5 an inclosed switch mechanism having provision for preventing an opening movement of the switch door so long as the switch is in a closed position and for preventing a closing movement of the switch so long as the door 10 is in an open position.

Another object of my invention is to provide a switch mechanism wherein the casting is made entirely of cast steel that is capable of resisting the pressures incident to 15 the internal explosions of accumulated gases.

Another object of my invention is to provide a switch housing with a sliding door and an interlocking mechanism whereby the 20 cover may be locked in a closed position so long as the switch is in a closed position and the switch will be retained in an open position when the cover is in an open position.

A further object of my invention is to 25 provide a switch mechanism having the above characteristics with means for operating the switch with a snap action and means for preventing any interference with the operation of the snap-action means.

These and other objects that will be made 30 apparent throughout the further description of my invention may be attained by means of the switch mechanism hereinafter described, and illustrated in the accompanying drawings, wherein

Fig. 1 is a view of a switch mechanism embodying features of my invention, the cover being removed;

Fig. 2 is a longitudinal section through 40 the switch housing, taken along the lines II—II of Fig. 1;

Fig. 3 is a longitudinal section similar to Fig. 2, showing the switch and cover in open position;

Fig. 4 is a transverse section through a fragment of the housing taken on the line IV—IV of Fig. 2; and

Fig. 5 is an exploded perspective view of the switch-operating mechanism.

Referring to the drawings, the switch mechanism includes a metal housing 1, a cover 10, a sliding door 2 disposed in the cover 10, a switch 4 mounted on a rotatable shaft 5, terminals 34 and 35 mounted on an insulating base 36, terminals 31 and 32

mounted on an insulated bracket 50, an interlocking member 6 mounted on a rotatable shaft 7 and movable with the switch by means of a toggle link 8, the toggle link 8 being pivoted to the switch 4 by pin 9 and 60 pivotally connected to the interlocking member 6 by the knee pivot pin 11 that extends inwardly through slot 22 in a bracket 30 which serves to limit movement of the knee pivot pin 11.

The switch 4 is biased toward an open position by a spring 12 that is connected, at one end, to a lever 21 secured to the switch 4, and, at the other end, to the bracket 30. The switch mechanism is provided with an operating handle 13 which is limited in movement by a slot 14 in the base 15 of the handle 13 and a projection 16 on the housing 1.

An interlocking member 17 is provided 75 on a shaft 18 and is movable with the handle 13. The interlocking member 17 is provided with an end-face 27 and an arcuate cam edge 37, an arcuate notch 19 and a face 29, the purposes of which are hereinafter set forth.

The interlocking member 6 is provided with an end-face 23 and an arcuate edge 54, the purposes of which are hereinafter set forth.

The switch 4 is for controlling the main circuit to which it is connected at terminals 31 and 32, and the housing incloses an auxiliary rotatable snap switch 33 of any preferred type for controlling certain auxiliary 90 circuits.

Terminals 34 and 35 are secured to an insulating base 36 and are provided with main fuse clips 38 and 39 and corresponding terminals 40 and 41 provided with corresponding fuse clips 42 and 43, respectively. Auxiliary fuse clips 44 and 45 are provided at the points between the clips 38 and 39 for the fuses connected to the auxiliary circuits. The auxiliary snap switch 33 is inclosed 100 within the housing and, therefore, any explosion which might result from the ignition of gases therein is prevented from being transmitted to the atmosphere.

Referring to the operation of my invention, 105 upon movement of the handle 13 in an opening direction, the interlocking member 17, which is movable with the handle 13, is rotated on the shaft 7 in a clockwise direction. The shoulder 19 of the interlocking member 110

17 engages the pin 11 and moves it past dead center of the pin 9 and the shaft 7, causing the switch to move to open position, with a snap action, by the spring 12. The pin 11 moves within the slot 22 which is connected to the switch 4 by the toggle link 8 and the interlocking member 6, causing the latter to rotate in a clockwise direction until its end-face 23 has moved out of the path of the 10 arcuate face 24 of the longitudinal web 25 on the under side of the door 2. The interlocking member is prevented from further clockwise movement by engagement of the pin 11 with the face 26 of the slot 22 when 15 the switch is in open position. The end-face 23 of the interlocking member 6 is disposed against the surface of the web 25 on the door 2 when the door is open and prevents closing movement of the switch so 20 long as the door is in that position.

The interlocking member 17, which is movable with the handle, prevents opening movement of the door by means of the face 27 pressing against the longitudinal web 25 of the door until the handle 13 is moved to its open position. The arcuate edge 37 of the interlocking member 17 extends above the arcuate edge 54 of the interlocking member 6 and thereby prevents any opening 30 movement of the door from interfering with the snap action of the switch 4 and interlocking member 6.

The snap action is made possible by the lost-motion connection between the interlocking member 17 and the interlocking member 6, as will be apparent from the drawings. As soon as the face 19 of the interlocking member 17 carries the pin 11 past dead center of the pin 9 and the shaft 7, 40 the switch will be moved to open position with a snap action by the spring 12, and the end-face 23 of interlocking member 6 will pass out of the path of the arcuate edge 24 of the door prior to the end-face 27 of interlocking member 17.

When the interlocking member 17 is moved to open position by the handle 13, both the face 23 of the interlocking member 6 and face 27 of interlocking member 50 17 will have passed out of the path of the web 25 of the door so that the door may then be moved to open position. As long as the door remains in an open position, the face 23 of interlocking member 6 and face 27 of 55 interlocking member 17 are pressed against the web 25 of the door and thereby prevent any closing movement of the switch so long as the door is in an open position.

Upon moving the door to its closed position, the switch 4 may be closed by moving the handle 13 toward closed position. Upon movement of the handle towards closed position, the arcuate edge 37 of the interlocking member 17, which is movable with the handle 13, engages the arcuate edge 24 of the

door and thus prevents opening movement of the door and the face 29 of the interlocking member 17 presses against the pin 11, moving it past dead center of the pin 9 and shaft 7 and causing the switch 4 to be moved to its closed position.

The arcuate edge 37 of the interlocking member 17, extending higher than the arcuate edge 54 of the interlocking member 6, prevents the arcuate edge 24 of the door from interfering with the closing movement of the interlocking member 6. The arcuate edge 37 of the interlocking member 17, pressing against the arcuate face 24 of the door, prevents opening movement of the door so long as the switch is in its closed position.

My invention provides a combination of two interlocking members one of which is movable with the switch and prevents any opening movement of the door when the switch is in closed position and any closing movement of the door so long as the switch is in open position. The other interlocking member, which is movable by the switch-handle is provided for protecting the interlocking member moved by the switch from any interference due to attempt to open the door before the switch is in open position.

Interlocking member 17, which is movable with the handle 13, actuates the second interlocking member 6 and, by means of the lost-motion connection between the two interlocking members, the interlocking member 6, which is movable with the switch, is permitted to reach its full open position prior to the interlocking member 17 movable by the handle.

The arcuate edge 37 of the interlocking member 17 is always in contact with the arcuate face 24 of the door when the interlocking member 6 is in movement either to an open or closed position and thereby prevents any pressure applied to the door from interfering in any way with the interlocking member 6. It thereby assures a snap action in the opening and the closing movement of the switch 4, as a result of which the interlocking member 6 reaches its full open or closed position prior to the interlocking member 17. It is often the case, in this type of a switch mechanism, that the operator endeavors to open the switch and the door at the same time. By the combination of the two interlocking members provided by this invention, the operator is prevented from moving the door towards an open position until the switch is opened and it will be seen from the drawings that it is likewise necessary for the door to be completely closed before any closing movement of the switch can take place.

It is often the case that gases accumulate inside the housings of switches of this type

and when the switch is opened the arc causes an explosion of the gases. The sliding door provided in my apparatus is of such construction that it is adapted to withstand the 5 maximum pressure exerted by the explosion of gases under such circumstances.

A groove is provided in the cover 10 to engage all edges of the sliding door. The edges of the door constitute tongues which 10 fit into the grooves provided in the cover. This construction also provides a tortuous path for any burning gases in traversing which they are cooled before they are permitted to escape into the atmosphere.

15 While I have described and illustrated only one embodiment of my invention, it will be apparent to those skilled in the art that various changes, modifications, substitutions, additions and omissions may be 20 made therein without departing from the spirit and scope of my invention as set forth in the appended claims.

I claim as my invention:

1. A switch mechanism comprising a 25 housing, a cover therefor, a switch within the housing, an interlocking member movable with the switch and interlocked with the cover for preventing opening movement of the cover so long as the switch is in closed 30 position and preventing closing movement of the switch so long as the cover is in open position, an operating handle, an interlocking member movable with the handle and so interlocked with the cover that the latter 35 is retained in closed position until the switch has been moved to open position in response to movement of the handle and a lost-motion connection between the switch and the handle.

40 2. A switch mechanism comprising a housing, a cover therefor, a switch mounted within the housing, an interlocking member movable with the switch and interlocked with the cover for preventing opening movement of the cover so long as the switch is 45 in closed position and preventing closing movement of the switch so long as the cover is in open position, an operating handle, an interlocking member movable with the 50 handle and interlocked with the cover for preventing opening movement of the cover when the switch is in closed position and for actuating the interlocking member movable with the switch for opening the switch 55 prior to the time at which the interlocking members move out of the path of the cover, a lost-motion connection between the handle and the interlocking member movable with the switch so that, upon the opening movement of the handle, the interlocking member carried by the handle actuates the interlocking member movable with the switch to cause an opening movement of the switch 60 prior to the time at which the interlocking members move out of the path of the cover.

3. A switch mechanism comprising a housing, a sliding cover therefor, a switch within the housing, an operating handle, an interlocking member movable with the handle, an interlocking member movable 70 with the switch, both interlocking members being interlocked with the cover for preventing opening movement thereof so long as the switch is in its closed position and for preventing closing movement of the switch 75 so long as the cover is in open position, a lost-motion connection between the operating handle and the switch whereby the interlocking member movable with the handle actuates the interlocking member movable 80 with the switch for opening the switch prior to the time at which the interlocking members permit opening movement of the cover.

4. A switch mechanism comprising a housing, a sliding cover therefor, a switch within the housing, an interlocking member movable with the switch and interlocked with the cover, an operating handle, an interlocking member movable with the handle and interlocked with the cover, a lost-motion 90 connection between the interlocking member movable with the handle and the interlocking member movable with the switch, whereby, upon movement of the operating handle in an opening direction, the interlocking member carried by the handle actuates the interlocking member movable with the switch, causing opening movement of the switch prior to the time at which the interlocking members permit opening movement 95 of the cover.

5. A switch mechanism comprising a housing, a sliding cover therefor, a movable switch within the housing, an interlocking member rotatably movable with the switch 105 and interlocked with the cover for preventing opening movement of the cover so long as the switch is in closed position and for preventing closing movement of the switch so long as the cover is in open position, an operating handle, an interlocking member 110 movable with the handle and interlocked with the cover, a lost-motion connection between the interlocking member movable with the handle and the interlocking member 115 movable with the switch whereby, upon movement of the handle, the interlocking member movable with the handle actuates the interlocking member movable with the switch to cause opening movement of the 120 switch prior to the time at which the interlocking members permit opening movement of the cover.

6. A switch mechanism comprising a housing, a cover therefor, a switch mounted within the housing, a plurality of interlocking members, an operating handle, means for so disposing the interlocking members that one interlocking member is movable with the switch and another interlocking mem- 125 130

ber is movable with the handle, both interlocking members being interlocked with the cover for preventing opening movement thereof so long as the switch is in its closed 5 position and for preventing closing movement of the cover so long as the switch is in an open position, and a lost-motion connection whereby, upon movement of the operating handle, the interlocking member 10 movable by the handle actuates the interlocking member movable with the switch to cause opening movement of the switch prior to the time at which the interlocking members permit the opening movement of the 15 cover, said interlocking members being so disposed as to prevent closing movement of the switch so long as the cover is in its open position.

7. In a switch structure, the combination 20 with a sliding cover, an operating handle having an interlocking member movable therewith, a rotatable switch having an interlocking member movable therewith and means for so disposing the interlocking 25 member movable with the operating handle that it will be interlocked with the sliding cover, of a lost-motion connection between the operating handle and the switch, whereby the interlocking member movable with 30 the handle actuates the interlocking member movable with the switch to cause opening movement of the switch before the interlocking member movable with the handle releases the cover.

8. A switch mechanism comprising a housing, a cover therefor having a door therein, a switch within the housing, an interlocking member movable with the switch and interlocked with the door for preventing opening movement of the door so long as the switch is in closed position and preventing closing movement of the switch so long as the door is in open position, an operating handle, an interlocking member movable 45 with the handle and so interlocked with the door that the latter is retained in closed position until the switch has been moved to open position in response to movement of the handle, a lost-motion connection between 50 the switch and the handle and a resilient member cooperating with the switch and the lost-motion connection to cause quick opening movement of the switch.

9. A switch mechanism comprising a housing, a cover therefor having a sliding door therein, a switch mounted within the housing, an interlocking member movable with the switch and interlocked with the door for preventing opening movement of the door so 60 long as the switch is in closed position and

prevent closing movement of the switch so long as the door is in open position, an operating handle, an interlocking member movable with the door and interlocked with the door for preventing opening movement of the door when the switch is in closed position and actuating the interlocking member movable with the switch for opening the switch prior to the interlocking member moving out of the path of the door, a lost-motion connection between the handle and the interlocking member movable with the switch so that, upon opening movement of the handle, the interlocking member carried by the handle actuates the interlocking 70 member movable with the switch to cause opening movement of the switch prior to the interlocking member moving out of the path of the door.

10. A switch mechanism comprising a 80 housing, a door therefor, a switch within the housing, an interlocking member mounted on a shaft within the housing and movable with the switch and interlocked with the door, an operating handle, an interlocking 85 member movable within the door and interlocked with the door, a lost-motion connection between the interlocking member movable with the door and the interlocking member movable with the switch whereby, 90 upon movement of the operating handle in an opening direction, the interlocking member carried by the handle actuates the interlocking member movable with the switch to cause opening movement of the switch prior to the interlocking member permitting opening movement of the door.

11. A switch mechanism comprising a housing, a sliding cover therefor, a switch within the housing, an operating handle, an interlocking member movable with the handle, an interlocking member movable with the switch, both interlocking members interlocked with the cover for preventing opening movement of the cover so long as 100 the switch is in its closed position and for preventing closing movement of the switch so long as the cover is in its open position, a lost-motion connection between the operating handle and the switch, whereby the interlocking member movable with the handle actuates the interlocking member movable with the switch for opening the switch prior to the interlocking member permitting opening movement of the cover.

In testimony whereof, I have hereunto subscribed my name this 13th day of April, 1927.

OLIVER S. JENNINGS.
